UNITED STATES PATENT OFFICE.

ARTHUR M. QUA, OF GRAND RAPIDS, MICHIGAN.

DESIGN FOR A VEST.

58,399.

Specification for Design.

Patented July 12, 1921.

Application filed April 1, 1919. Serial No. 286,750. Term of patent 3½ years.

To all whom it may concern:

Be it known that I, ARTHUR M. QUA, a citizen of the United States, and a resident of the city of Grand Rapids, in the county of Kent and State of Michigan, have invented a new, original, and ornamental Design for a Vest, of which the following is a specification, reference being had to the accompanying drawing, forming a part thereof.

The figure of the drawing is a perspective view of a vest showing my new design.

I claim:

The ornamental design for a vest, substantially as shown.

In testimony whereof, I affix my signature.

ARTHUR M. QUA.
